UNITED STATES PATENT OFFICE.

PEACHANN PFEFFERLE AND MARGARET E. PFEFFERLE, OF COLUMBUS, OHIO.

DESIGN FOR A SUIT OF COVERALLS.

55,573.

Specification for Design. Patented June 29, 1920.

Application filed May 29, 1919. Serial No. 300,742. Term of patent 7 years.

To all whom it may concern:

Be it known that we, PEACHANN PFEFFERLE and MARGARET E. PFEFFERLE, citizens of the United States, residing at Columbus, in the county of Franklin and State of Ohio, have invented a new, original, and ornamental Design for a Suit of Coveralls, of which the following is a specification, reference being had to the accompanying drawing, forming a part thereof.

The figure is a front view of a suit of coveralls showing our new design.

We claim:

The ornamental design for a suit of coveralls as shown.

PEACHANN PFEFFERLE.
MARGARET E. PFEFFERLE.
